(57) **CLAIM**

The ornamental design for a shoe outsole bottom as shown and described.

DESCRIPTION

FIG. 1 is a perspective view of a shoe outsole bottom in accordance with my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dash-dash broken lines shown in the drawings represent portions of the shoe upper and midsole periphery that form no part of the claimed design. The dash-dot-dash broken lines define the bounds of the claimed design and form no part thereof.
